Primary Examiner — Melanie Pellegrini

(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

1.8 : Top view of the bracelet open

The bracelet comprises a band, the ends of which are tapered and interconnected by a pin buckle, as well as a plurality of flexible decorative elements in the form of anchor chain links; the decorative elements are placed next to the outer surface of the band and held in position by a strap, the ends of the strap being attached to those of the band, and the strap extending partly over the ends of the decorative elements and partly on the inside of the band after passing through the slits in the latter.
